UNITED STATES PATENT OFFICE.

GRANVILLE A. HUMASON, OF HOUSTON, TEXAS, AND CHARLES G. LAMBERT, OF SHREVEPORT, LOUISIANA, ASSIGNEES OF ONE-THIRD TO J. A. LOGAN, OF HARRIS COUNTY, TEXAS.

OIL VAPORIZER AND BURNER.

Application filed February 12, 1926. Serial No. 87,744.

This invention relates to new and useful improvements in an oil vaporizer and burner.

One object of the invention is to provide a device of the character described whereby crude oil may be thoroughly broken up and vaporized, and rendered completely combustible.

Another object of the invention is to provide a device of the character described by the use of which impure crude oil, that is crude oil which is mixed with water, sediment and other impurities, may be thoroughly broken up and treated, to the end that the oil will readily separate from the water and foreign matter therein.

A further feature of the invention resides in the provision of a device of the character described embodying a novel construction whereby the feed of the oil, through the device may be easily regulated.

A still further feature of the device resides in the provision of means for preheating the oil as well as for mixing the same with steam, air, or gas, in the process of vaporization.

With the above and other objects in view this invention has particular relation to certain novel features of construction, operation and arrangement of parts, an example of which is given in this specification and illustrated in the accompanying drawings, wherefore in:

Figure 1 shows a longitudinal sectional view of the device.

Figure 2 shows a cross sectional view taken on the line 2—2 of Figure 1.

Figure 3 shows a cross sectional view taken on the line 3—3 of Figure 1.

Figure 4 shows a fragmentary longitudinal sectional view of the device showing another type of controlling means for regulating the feed, or flow of oil, through the device, and

Figure 5 shows a cross sectional view thereof, taken on the line 5—5 of Figure 4.

Referring now more particularly to the drawings, wherein like numerals of reference designate similar parts in each of the figures, the numeral 1 designates an outer tubular jacket whose free end has the nozzle 2 threaded thereon. This nozzle has a central passageway 3, therethrough, whose outer end is flared and whose inner end has an inwardly diverging seat 4. The jacket is anchored to the body 5, which is of the general form of a

T-connection, said jacket preferably having a threaded connection with said body.

An oil line 6 is connected into the body 5 and is preferably formed with an enlarged heating chamber 7. There is a pressure fluid nozzle 8 within the jacket 1 which is held concentrically therein by the spacer lugs 9 on the inside of said jacket. The nozzle 8 has a central axial, steam duct 10 therethrough into the inner end of which the steam pipe 11 is threaded and threaded onto the inner end of the nozzle 8 there is an air or gas line 12. The jacket and the lines 11 and 12 are concentric and spaced apart to provide passageways 13 and 14 for the oil and steam, respectively, as well as the passageway 15 for air or gas. The nozzle 8 has a plurality of ducts 15' leading from the chamber 15 and terminating in the passageway 3. The outer end of the pressure fluid nozzle 8 is tapered to conform to the shape of, and is adapted to seat in, the seat 4.

The steam pipe 11 and the air or gas pipe 12 extend back through the body 5, and said steam pipe is connected with a steam line 16 which is formed into a coil 17, in the chamber 7, and is controlled by the hand operable shut off valve 18.

There is a suitable connecting nipple, as 19, Figure 1, or 19', Figure 4, connected into the body 5. The pipes 11 and 12 have a fixed relation with the nipple 19 and with the body 5, as illustrated in Figure 1, but are adjustable through the nipple 19' and body 5, as illustrated in Figure 4.

There is a gas or air line 20 connected into the chamber 15, through the nipple 19, or 19', and this line 20 has two branches 21, 21, one for air and the other for gas.

In the form shown in Figure 1 the jacket 1 has a spur gear 22 fixed thereon and in mesh with a pinion 23 which is fixed on an adjusting or controlling shaft 24. This shaft is mounted to rotate in the bearings 25 formed on the body 5 and has a hand grip 26 by means of which it may be turned. By the manipulation of the shaft 24 the jacket 1 may be rotated and by its screw connection with the body 5, thus adjusted so as to adjust the seat 4 relative to the operating end of the nozzle 8. This seat 4 may thus be entirely closed to shut off the flow of oil through the passageway 3, or the seat 4 may be partly or entirely opened.

In the form shown in Figure 4 there is an adjusting cap 27 threaded onto the nipple 19' and having a swiveling but operative connection with the pipe 11. By the manipulation of this nut the pipe 11, and with it the nozzle 8, may be adjusted relative to the seat 4 and said seat closed or opened in the manner and for the purpose above explained.

- 10 10 The oil may be delivered by pressure, or gravity, into the chamber 13 and steam is discharged, under pressure, through the pipe 11 and will catch up and mingle with and vaporize said oil. Air, or gas, may be delivered under pressure, through the chamber 15 and ducts 15' and will also mingle with and further vaporize the oil.
- 15 15

For cleansing purposes there is a normally closed connecting nipple 28 connected into the oil chamber 13. A fluid pressure line may be connected onto this nipple, if the device becomes clogged, and the offending, clogging material thereby dislodged.

- 20 20 The movable parts have suitable packing interposed between them so that all joints will be fluid tight.

The device herein described may be used as an oil burner and will be found to be very efficient for the reason that it will 30 thoroughly vaporize the oil and mix it with steam and air. It will also prove efficient in the treatment of impure crude oil. For such purpose the oil may be delivered

through it into a vat or tank, the process of vaporization described will so break up the oil that the water and impurities will readily settle and the pure oil will collect on top and can be readily drawn off.

What we claim is:

A device of the character described including a tubular jacket, a discharge nozzle carried by one end thereof and a T connection attached to the other end thereof, an oil line entering said T connection, a pressure fluid nozzle within said jacket provided with an axial steam duct, a steam pipe one end of which is threaded into said duct, an air pipe surrounding and spaced from said steam pipe, one end of which is anchored to said pressure fluid nozzle, said last mentioned nozzle having ducts for the passage of air delivered through said air pipe, a connecting nipple attached to said T connection and aligned with said jacket, said air and steam pipes being adjustable relative to said connecting nipple, an adjusting cap threaded on to said nipple and having a swiveling but operative connection with said steam pipe and by the manipulation of which said air and steam pipes and said pressure fluid nozzle may be adjusted relative to said discharge nozzle.

In testimony whereof we have signed our names to this specification.

GRANVILLE A. HUMASON.
CHARLES G. LAMBERT.
